(57) **CLAIM**

The ornamental design for a front bumper skid plate, as shown and described.

DESCRIPTION

FIG. 1 is a front perspective view of a front bumper skid plate on a vehicle;

FIG. 2 is an enlarged view of the portion of FIG. 1 depicting the front bumper skid plate;

FIG. 3 is a front orthogonal view of the front bumper skid plate;

FIG. 4 is a left side orthogonal view of the front bumper skid plate, where the right side orthogonal view is substantially a mirror image;

FIG. 5 is a top orthogonal view of the front bumper skid plate; and,

FIG. 6 is a bottom orthogonal view of the front bumper skid plate.

The broken lines present in the drawings are included for the purpose of illustrating portions of the article which form no part of the claimed design.
